Attby. J.

UNITED STATES PATENT OFFICE

1,931,525

TANK

Harry C. Boardman, Chicago, Ill., assignor to
 Chicago Bridge and Iron Company, Chicago,
 Ill., a corporation of Illinois

Application December 16, 1931
 Serial No. 581,493

5 Claims. (Cl. 220—26)

This application relates to improvements in tanks and, more especially, storage tanks adapted for containing liquids.

One of the features of my invention is the provision of a floating roof with improved means for sealing the space between the edge of the roof and the wall of the tank.

Other features and advantages of my invention will appear more fully as I proceed with my specification.

10 In those forms of devices embodying the features of my invention shown in the accompanying drawing—

Figure 1 is a view in side elevation partly in vertical section; Fig. 2 is an enlarged fragmentary view showing the method of making the seal; and Fig. 3 is a view similar to Fig. 2 showing a modified form.

As shown in the drawing, 10 is a cylindrical tank for the storage of liquid 11.

15 Floating on the liquid is a circular deck or pan 12 having an upstanding outwardly flared rim 13, the upper edge of which is preferably curved inwardly slightly, as indicated by 13^a.

20 The deck 12 and the rim 13 are preferably made of sheet metal. The rim 13 is high enough and thin enough so that it is flexible and distortable and its upper edge has a fixed perimeter. It is contemplated that the tank wall 10 will be

25 made as cylindrical as possible and as free as possible from obstructions or bumps on the inside of the tank should be butt-welded and not overlapped. Even though the circumference of the tank wall 10 is substantially

30 uniform throughout its height, there may be considerable variations out of round. The diameter of the flat deck portion 12 of the floating roof is somewhat smaller than the diameter of the tank. The rim 13 is flared outwardly and

35 high enough and thin enough so as to be distortable. Consequently, as the roof rises and falls, the upper edge of the rim which contacts with the tank wall may be distorted out of round to conform to the shape of the tank wall

40 at various heights. The line of contact between the rim 13 and the tank wall 10 is indicated by 14.

The modified form shown in Fig. 3 is substantially the same, with the following exceptions.

45 Numeral 110 indicates the tank wall and 112 the flat deck portion floating on the liquid. Numeral 113 indicates an upstanding outwardly flared peripheral rim. The upper edge of this rim, however, does not contact directly with the tank wall 110 but carries a depending circular band of metal 115 in the nature of a continuous shoe surrounding the tank wall. The upper edge of this band is curved inwardly, as indicated by 115^a, and the lower edge similarly curved inwardly, as indicated by 115^b. The shoe may be

attached to the rim 113 in any suitable manner, as by welding. By providing the shoe, a longer contact is provided with the tank wall 110. The rim 113 and also the shoe 115 are made wide enough and thin enough so that they will be distortable to conform to variations out of round of the tank wall 110.

50 Floating roofs of the character referred to are frequently used on oil storage tanks for the prevention or lessening of evaporation losses.

55 While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

60 What I regard as new, and desire to secure by Letters Patent, is:

65 1. A cylindrical tank adapted to contain liquid and a circular roof adapted to float on liquid in the tank, said roof having a flat sheet portion with a diameter smaller than the diameter of the tank and a peripheral upstanding outwardly flared rim with its upper edge of fixed perimeter and in contact with the wall of the tank, said rim being sufficiently high and flexible 70 to permit its upper edge to be distorted out of round.

75 2. Apparatus as claimed in claim 1, in which the upper edge of the rim is curved inwardly.

80 3. A cylindrical tank adapted to contain liquid and a circular roof adapted to float on liquid in the tank, said roof having a flat sheet portion with a diameter smaller than the diameter of the tank and a peripheral upstanding outwardly flared rim with its upper edge of fixed perimeter and a depending circular shoe 85 carried by the upper edge of the rim, said shoe being distortable and lying in contact with the wall of the tank.

85 4. Apparatus as claimed in claim 3, in which the upper and lower edges of the shoe are curved inwardly.

90 5. A cylindrical tank adapted to contain liquid and a circular roof adapted to float on liquid in the tank, said roof having a flat sheet portion with a diameter smaller than the diameter of the tank and a peripheral upstanding outwardly flared rim with its upper edge of fixed perimeter and with a part carried by its upper edge in contact with the wall of the tank, said rim being sufficiently high and flexible to permit its upper edge to be distorted out of round.

HARRY C. BOARDMAN.
